TUBE SUPPORT FOR HEATERS

Otto C. Schable, Mount Kisco, N. Y., and Edward Francis Tibbets, Cos Cob, Conn., assignors to The Lummus Company, New York, N. Y., a corporation of Delaware

Application December 23, 1949, Serial No. 134,646

4 Claims. (Cl. 122—6)

1

This invention relates to improvements in tube-supporting means for heaters of a type commonly employed for the heating of hydrocarbon fluids; for example, to distillation or cracking temperature. In a common form, such a heater includes a furnace chamber within which fuel is combusted, and tubes through which a fluid is passed for heating from said combustion by either radiant or convection heat, or both. The tubes are usually supported at spaced points along their length by metal members secured to the furnace chamber structure. When the tubes are arranged for convection heating by the hot combustion gases the tube supports are also exposed to contact by the gases and when the latter contain certain corrosives derived from the fuel employed the supports are subject to corrosive attack. Such attack is particularly severe when the fuel is oil containing vanadium and sulfur. When vanadium oxides and sulfur compounds occur in the combustion gases the metal of the tube supports is vulnerable to attack thereby at temperatures of 1250° F. and above. In fact, the metal then corrodes so rapidly that in a short time the tube supports break and permit the tubes to sag. Thus, a serious problem has existed in cases where heaters are dependent, for reasons of convenience and economy, upon vanadium-bearing fuel oils. This problem has defied metallurgical solution; no suitable metal or alloy has been found which will resist corrosion by vanadium oxides.

Important objects of the present invention are to provide a tube support with means for effectually shielding the metal of the support from contact with the combustion products and corrosion agents therein; to provide a tube support with a sheathing or jacket designed to exclude the combustion gases from the metal body of the support; and to provide such a sheathing formed of ceramic refractory material and designed to render it durable under the high temperatures of the heater.

Other objects and advantages of the invention will appear from the following description taken in connection with the accompanying drawings.

In the drawings:

Fig. 1 is a vertical sectional view of a heater embodying the invention;

Fig. 2 is a side elevation, upon a larger scale, of one of the improved tube supports and its suspension means and also a portion of an adjacent tube support, tubes engaged by said supports being shown in cross section;

Fig. 3 is an enlarged vertical section on the line 3—3 of Fig. 2;

2

Figs. 4, 5 and 6 are enlarged detail sections on the lines 4—4, 5—5 and 6—6, respectively, of Fig. 2;

Fig. 7 is a view similar to Fig. 2 showing a modified form of the invention;

Fig. 8 is an enlarged vertical section on the line 8—8 of Fig. 7; and

Fig. 9 is a detail section showing anchorages between the body of the tube support and the reinforcing networks of the sheathing.

In Fig. 1 the improved tube supports are shown as employed in a heater for hydrocarbon fluids of the type disclosed in reissued U. S. Patent 21,396 dated March 12, 1940. This heater has a combustion chamber defined by side walls 1, opposite end walls, one of which is shown at 2, a hearth 3 and a bank of horizontal roof tubes including a lower row of tubes 4 and an upper row of tubes 5 which support a diffusion baffle formed by tile 6. Such a baffle is disclosed in U. S. Patent 2,147,610. A dividing wall 6a extends from the hearth 3 to a point short of the roof bank. Each of the side walls 1, bears a vertical bank of horizontal tubes 7. The hearth has burners 8 distributed over its area, and the end walls may also be provided with burners 9 at opposite sides of the dividing wall 6a. A roof structure 10 spaced above the diffusion baffle defines therewith a plenum chamber 11 which opens at one end thereof into a convection heating chamber 12 defined by one of the side walls 1, an outer wall 13 and a bottom wall 14. One or more banks of tubes 15 extends through the convection chamber and the latter has an outlet 16 for combustion gases located below the tubes and communicating with a stack, not shown. The present invention is shown as embodied in hanger members S employed to support the tubes 4 and 5. However, the invention may be embodied in members S' which support the tubes 7 upon the side walls or in any tube supports which are disposed for contact with hot combustion gases.

Referring to Figs. 1 to 6 inclusive, the structure of each tube support S includes a body 17 preferably formed of a high heat resistant metal alloy such as 25—12 chrome-nickel, for example. In the present instance the body is in the form of a flat plate in a vertical plane. The plate has recesses for receiving the tubes 4 and 5. There is a horizontal row of recesses in the form of holes 18 to receive the lower tubes 4 and a horizontal row of recesses in the form of notches 19 to receive the upper tubes 5. The holes 18 are substantially larger than the tubes therein, and the notches 19 are wider than the diameter of the tubes 5. The

body is also formed with upwardly extending tongues 20 which are bolted, as at 21, to suspension members 22, and the latter are anchored at their upper ends in any suitable manner to the roof structure 10.

Each tube support S has its body encased in a sheathing 23 of ceramic refractory material. This material is moldable and air-setting and may be a high alumina super duty clay, chrome ore, chrome magnesite or kaolin, for examples. The material is molded over the side faces and most of the edges of the metal body to form a sheathing, one to two or more inches in thickness.

In the construction of the sheathing the metal body 17, or core of the tube support, is provided with a reinforcing structure formed of networks of strands 24, preferably of wire. These are trained over anchoring elements borne by the body 17. Some of the anchoring elements are spaced over the opposite side faces of the body and others are spaced along edges of the body. As shown in Fig. 4, those on the faces of the body are in the form of hooks 25 of wire having shanks which are bent inward and welded as at 26, to the body. Fig. 5 shows a pair of the anchoring elements borne by the upper edge of the body. There, a wire saddle 27 straddles the edge, and depending hooks 28 have a shank portion resting on the saddle. A pair of these hooks may be formed of a single strand of wire, and the hooks and saddle are welded together. Horizontal strands 30 of wire extend parallel to and spaced from each face of the body 17 and are supported by the hooks 28 in a position between the holes 18 and the recesses 19. Fig. 6 shows one of a number of pairs of anchoring elements spaced along the lower edge of the body. Each pair of elements may be formed of a single strand 29 of wire bent upwardly into an approximate V-form and bent downwardly at the ends to form hooks. A strand 30a of wire runs along the lower edge of the body in spaced relation thereto and is welded to the pairs of anchoring elements. These elements straddle a strip 31 of wood or other suitable material which extends along the lower edge of the body and holds the elements suitably spaced from said edge. Said elements and the strip 31 are supported in place by the wire networks which are suspended from the upper anchoring elements and from the strand 30. The various anchoring elements are formed and arranged to hold the reinforcing strands spaced substantially from the body 17.

Before molding the sheathing over the body 17 the face and edge surfaces of the latter which are to be shielded by the sheathing are covered with a layer 32 of material which may, for examples, be pasteboard, oil, grease or paint. Then, the ceramic material, in a plastic state, is molded over the body 17 and the reinforcing structure so that the latter is intermediate the thickness of the material and so that all surfaces of the body are covered except bottom surfaces 33 of the holes 18 and of the notches 19, which receive the tubes, and the upper end portions of the tongues 20. The ceramic material is so molded as to form holes 18a which are smaller than the holes 18 and tangent to the lower side thereof and larger than the tubes 4.

A ceramic sheathing 34 encases the upper end portion of each tongue 20 and the suspension member 22 attached thereto. This sheathing may be integral with the sheathing 23 which

encases the body of the tube support or it may be separately formed of the same ceramic material. For reinforcing the material a strand 35 of wire is helically wound around the tongue and the suspension member 22. The ceramic material is molded over and around the reinforcement and covers the tongue and the suspension member from the tube support to the roof structure 10, the reinforcement being at an intermediate position in the thickness of the sheathing. Preferably the surfaces of the tongue, the suspension member and the joint therebetween which are covered by the sheathing 34 are also preferably covered with a layer of material such as oil, grease, paint or pasteboard, for examples, before the ceramic material is molded thereover.

The layer 32 of material between the body 17 of the tube support and the sheathing 23 prevents bonding of the ceramic material of the sheathing to the surfaces covered thereby. In service, said layer and the wood strip 31 will burn away and leave clearance between the metal body and the ceramic sheathing and enable them to expand and contract independently and thereby prevent cracking of the ceramic material under temperature changes. Similarly, the layer of material between the ceramic sheathing 34 and the tongues 20 and the suspension members 22 prevents bonding of the sheathing to the surfaces covered thereby and enables the ceramic sheathing and the metal parts to expand and contract independently and prevent cracking of the sheathing under temperature changes.

In Figs. 7, 8 and 9 the structures of the tube support and its suspension means are similar to these just described except for modification of the reinforcing means for the ceramic sheathing. In said figures, parts similar to the first described form of the invention are designated by the same reference characters. In the modification, the reinforcing networks are anchored to the body 17 of the tube support by elements 36. Each of these is formed of a short straight piece of wire welded at one end to the body 17, as at 37, and extending at right angles thereto and having its outer end portion bent at an angle to the body of the element. The elements 36 are suitably distributed over the side faces and the edges of the body including the edges defining the holes 18, and the wire strands 24 are trained thereover to form the networks for reinforcing the ceramic sheathing.

In Fig. 1 the improved tube supports S are shown as employed for supporting the roof tubes 4 and 5 for the reason that such tubes and their supports are disposed across the outlet of the combustion chamber in the path of escaping hot combustion gases and corrosives borne thereby. When ordinary unprotected metal tube supports are employed in such a position and when highly corrosive vanadium oxides such as pentoxide or trioxide are present in the combustion gases and the gases are above a certain temperature the supports corrode rapidly to such a degree that they soon break under the weight of the tubes and permit the tubes to sag. Ordinarily, the fluid within the tubes cools them sufficiently to render them substantially immune to corrosion by such oxides. The tube supports however, are quite vulnerable.

The present invention provides for effectual protection of the tube supports from attack by vanadium oxides or other corrosives in the combustion gases by providing for exclusion of the

gases from contact with all surfaces of the tube supports. The only metal surfaces not covered by the ceramic sheathing are the small surfaces 33 at the lower side of the tube-receiving holes 18 and the notches 19. These surfaces are left bare in order that they may directly contact the tubes and provide for transmission of the tube load directly to the metal body of the tube support instead of to the ceramic sheathing which might fracture under the load. In service, said surfaces 33 are covered and protected by the tubes, which also cool the surfaces, so that the gas exclusion is complete.

In both forms of the invention the wire reinforcing networks and their anchoring elements will be of a material to resist the high operating temperature. For examples, suitable materials are 18-8 or 25-20 chrome-nickel.

While two satisfactory forms of the invention are disclosed it will be understood that the present disclosure is merely illustrative and in nowise limiting and that the invention comprehends such modifications as will come within the scope of the following claims.

We claim:

1. A tube support for a heater of a type having horizontally extending tubes for circulating a fluid to be heated and in which said tubes are disposed within a heating chamber in a position in which they are subjected to contact with hot gaseous products of combustion, comprising a vertical metal plate having spaced recesses each formed to receive at least a substantial portion of the cross section of one of said tubes, a sheathing of molded refractory non-metallic material covering the faces and edges of said plate including the major portion of the surfaces defining said recesses, a minor portion only of the surface defining each recess and located at the bottom of the recess to be covered by the tube, being bare, for under support of the tube by contact

with the metal plate, and reinforcing structure comprising crossed strands of metal arranged to prevent cracking of the sheathing in any direction extending over the opposite faces of the plate and within the thickness of the sheathing and with the material of the sheathing molded there-around, the adjacent surfaces of the sheathing and the plate being free from bond therebetween, for independent expansion and contraction of the plate and the sheathing.

2. The tube support of claim 1 wherein at least one of said tube-receiving recesses is located entirely within the contour of said plate and is surrounded by the plate and said sheathing.

3. The tube support of claim 1 including metal extensions leading upward from said plate for supporting same by suspension, a sheathing of molded refractory non-metallic material encasing each of said extensions, and metal reinforcement structure within said sheathings and with the material of the latter molded thereto.

4. The tube support of claim 1 including bifurcated elements within said sheathing straddling edges of said plate and with their legs connected to said reinforcing structure to anchor same to the plate.

OTTO C. SCHAUBLE.
